UNITED STATES PATENT OFFICE.

HARVEY S. MUNSON, OF NEW HAVEN, CONNECTICUT.

PAPER BOX.

SPECIFICATION forming part of Letters Patent No. 293,061, dated February 5, 1884.

Application filed October 29, 1882. (No model.)

To all whom it may concern:

Be it known that I, HARVEY S. MUNSON, a citizen of the United States, residing in the city of New Haven, county of New Haven 5 and State of Connecticut, have invented certain new and useful Improvements in Boxes, fully described and represented in the following specification and the accompanying drawings, forming a part of the same.

10 In said drawings, Figure 1 illustrates the blank from which the box is made. Figs. 2 and 3 are perspective views, illustrating two steps in the manipulation of said blank in the operation of setting it up or forming the box. 15 Fig. 3 shows the box in condition to be filled with its contents. Fig. 4 illustrates the box in its closed condition.

The improvements effected by this invention relate to that class of boxes, preferably 20 made of paper or similar material, in which the box proper and its cover are permanently united by a hinge-like joint, enabling the cover to be opened and closed without affecting the box-body, and which cover and box in the 25 form of a flat blank may be conveniently shipped or stored, and yet be readily set up in box form and secured for use through locks provided by the material composing the box.

The invention consists in a box the body 30 and cover of which are formed in a single piece or blank, fashioned, creased, or scored; so as to enable it to be laid flat for shipment or storage, or to be set up into hollow form for use, and retained in such form by locking- 35 tongues, and also provide the box with a double bottom, the flaps of which are locked into place, and thus prevented from protruding upward into the interior of the box, all of which will be more particularly hereinafter 40 explained and claimed.

In carrying out this invention a blank of general rectangular form is cut, scored, or creased and incised, as in Fig. 1, thus providing a box consisting of a bottom, A, bottom flaps, B C, a front, D, a back, E, side flaps, F G and H I, end-closing flaps K L, and a cover consisting of a top, J, and tucking-flap M. The scoring or creasing to provide weakened folding-joints is made on the lines 5 6 to enable the bottom 45 flaps, B C, to fold inwardly over the bottom A; on the lines 7 8 to enable the front D and

back E to fold up at right angles to the said bottom; on the lines 9 10 and 11 12 to enable the side flaps, G I and F H, to bend inwardly at right angles to the said front and back; on 55 the lines 13 14 to enable the closing-flaps K L to be folded over the box end, and on lines 15 16 to enable the cover J to be folded over the box end, and its flap M to be entered into the box end. It is incised on the lines 21 22 and 60 17 18 to free the bottom flaps, B C, from the side flaps F H and bottom A, and on lines 19 20 to free the end closing-flaps K L from the cover-top J. Its side flaps F H are incised on the angular lines shown to provide the locking-pockets 3 4, and the side flaps G I have angular pieces removed to form the locking-tongues 1 2. All of these operations are preferably performed by dies, but may be accomplished by hand or other operations. Thus 70 prepared, the blank is capable of being brought into box form by the following manipulation: The sides G I are bent upward at right angles to the front D, as in Fig. 2, and the bottom flaps, C B, are folded inward so as to 75 stand at right angles to said sides G I. The sides F H are then similarly bent at right angles to the back E, carrying with them the top flaps, K L, in like arrangement with respect to the top J. These parts are then carried 80 bodily upward, so that the bottom A, bending upon the line 7, lies snugly against the bottom flaps, C B, while the back E bends upon the line 8 as the sides F and H are entered within the sides G I. When these sides F H lie 85 within the sides G I, the tongues 2 1 are entered into the pockets 4 3, thus locking all the sides together, as in Fig. 3, and confining the bottom flaps, B C, in place.

To close the cover the top flaps, K L, are bent 90 inwardly on the lines 19 20, the top J on the line 15 and the closing-flap M on the line 16, the latter being entered behind the front D. In this structure it will be observed that one bottom flap, as B, overlies its companion, as 95 C, and that the two are confined between said bottom and the lower edges, 23 24, of the sides F H, thus being firmly secured flatly upon said bottom, and held there against any tendency to curl up or project inwardly or toward 100 the interior of the box in a position to abridge the cubical area of the box or interfere with

the contents thereof, either in filling or removing the same. Such locking also imparts such strength to the parts as to greatly reduce the tendency of the box sides to bulge or break away from their fastenings by reason of the pressure of its contents or from the strains due to handling.

The locking-tongues 1 2 are located at the free edge or extreme outer corners of the sides 10 G I, and are secured by entering upwardly into the pockets 3 4, which are located at the back edge of the sides F H, said tongues thus having a considerable extension upward beyond the horizontal or upper incision forming 15 said pockets, which affords a corresponding extent of lateral bearing-surface for them at the corners of said pockets formed by uniting the horizontal and vertical incisions constituting such pockets. By this structure of fastening it will be observed that the extreme 20 edges of the side flaps G I are held snugly along the sides F H, thus affording no projection liable to curl up and be caught, and normally have little or no tendency to protrude 25 or bend outward, while, when pressure is exerted from the interior, any tendency to bulge is counteracted in both directions.

The locking-pocket, formed, as it is, by a right-angular incision, is such that it may be 30 pressed freely inward to admit the passage of the locking-tongue, and yet afford at the rear end of its horizontal incision a wedge-like structure, into which the edge of the tongue may be forced, and thereby pinched and securely held 35 against longitudinal displacement, while the free or wing part of the pocket does not weaken the holding-point against which the tongue presses, and is held against lateral displacement.

40 What is claimed is—

1. A blank consisting of the general rect-

angular form shown, having folding lines 5 6 7 8 9 10 11 12 13 14 15 16 and incisions 21 22 17 18 19 20, whereby the folding parts necessary to constitute a box and cover are provided, and having the incisions forming the tongues 1 2 and pockets 3 4, whereby said parts are locked into hollow or box form, substantially as described.

2. A box formed of a single piece of material cut, scored, and incised to form the bottom A, bottom flaps, B C, front D, back E, sides F G H I, locking-tongues 1 2, and locking-pockets 3 4, said parts being folded, so that the bottom flaps are confined between the 55 bottom A and the lower edges of the sides F H, substantially as described.

3. A box and cover formed of a single piece of material cut, scored, and incised to form the bottom A, bottom flaps, B C, front D, 60 back E, sides F G H I, top J, top closing-flaps, K L, tucking-flap M, locking-tongues 1 2, and locking-pockets 3 4, said parts being folded so that the bottom flaps are confined between the bottom A and lower edges of the 65 sides F H, and the locking tongues and pockets are arranged to confine the free edges of the sides G I, substantially as described.

4. A locking-pocket for the parts of boxes made from paper or similar material, the 70 same being formed by a right-angular incision, whereby the locking-tongue is free to enter, and is nipped securely at one edge, substantially as described.

In testimony whereof I have hereunto set 75 my hand in the presence of two subscribing witnesses.

HARVEY S. MUNSON.
